CONTROL MECHANISM

Harold F. Elliott, San Francisco, Calif.

Continuation of application Serial No. 424,234,
December 24, 1941. This application filed Au-
gust 7, 1946, Serial No. 688,920.

22 Claims. (Cl. 192—142)

1

This invention relates generally to mechanism for determining a predetermined control position for controllable apparatus and in particular to radio control mechanism adapted for selective actuation to accomplish a predetermined tuning position for radio tuning apparatus. This application is a continuation of application Serial No. 424,234, filed December 24, 1941, now abandoned.

It is an object of this invention to provide improved mechanism for defining a predetermined control position for controllable apparatus.

A further object of this invention is to provide improved control mechanism for radio tuning apparatus.

Another object of this invention is to provide mechanism for reversible controllable apparatus capable of moving the controllable apparatus in either direction of movement to a predetermined control position.

Yet another object of this invention is to provide a rotary control unit for controllable apparatus adapted for assembly axially of its axis of rotation and including lost-motion means of a construction such that a plurality of the control units can be stacked in axial alignment in a very minimum of space.

A still further object of this invention is to provide a control unit for tuning apparatus including gear elements operating with high gear ratios so that inaccuracies in tuning are appreciably decreased when transmitted to the tuning apparatus to accomplish accurate tuning in a commercially practical device.

A further object of this invention is to provide control mechanism for accomplishing a predetermined rotation of a rotary structure to a stop position.

Another object of this invention is to provide rotary control mechanism for rotatable controllable apparatus which is capable of accurately and precisely stopping the apparatus at any one of a plurality of positions within an operating range of any desired number of revolutions, thus providing great flexibility in both the design of the control mechanism and the controllable apparatus.

Still another object of this invention is to provide rotary control mechanism adapted for operation in two directions of rotation from a unidirectional motor to a predetermined control position.

A particular feature of this invention is found in the provision of a control unit which is precision operating and yet comprised of stamped

2

or like easily worked parts to provide an inexpensive and sturdy structure.

Yet another feature of this invention is found in the provision of a tuning unit having a plurality of control units axially aligned on a rotary control shaft and operating individually thereon to rotate the shaft to predetermined control positions. Each control unit includes a member adjustably supported on the control shaft, with one of the control units being adapted to coact with manually operated means for clamping the adjustable members in adjusted positions.

Further objects, features, and advantages of this invention will become apparent from the following description when taken in connection with the accompanying drawings in which:

Fig. 1 is a plan view of a radio tuning unit embodying one form of the improved control mechanism of this invention;

Fig. 2 is an elevational view of the unit in Fig. 1 as seen along the line 2—2 in Fig. 1; showing the relative arrangement of the various parts of the control mechanism and the axial aligning of the tuning control units;

Fig. 3 is a diagrammatic illustration of the control mechanism showing its operative connection with the tuning means and the driving motor for the tuning apparatus;

Fig. 4 is a fragmentary sectional view taken along the line 4—4 in Fig. 2 showing a portion of the means for clamping the control units in their axially stacked relation;

Fig. 5 is a view partly in section taken approximately along the line 5—5 in Fig. 2;

Fig. 5a is a fragmentary sectional view as seen along the line 5a—5a in Fig. 2;

Fig. 6 is an enlarged sectional detail view as seen along the line 6—6 in Fig. 5 showing a complete control unit and the stack clamping means;

Fig. 22 shows a circuit diagram for embodying the centrifugal switch of Fig. 21.

In practicing this invention there is provided control mechanism adapted for use with rotatable controllable apparatus and operated by a unidirectional motor to accurately rotate the controllable apparatus in either direction of rotation to a predetermined control position. The control mechanism utilizes rotatable operating elements constructed and assembled to provide for multi-revolution lost motion within the mechanism to permit the use of a plurality of control units within the mechanism without mutual interference. This lost motion, which occurs entirely in the control mechanism, permits a high gear ratio within a very small space between the controllable apparatus and the control mechanism. Inaccuracies in obtaining predetermined control positions of the controllable apparatus are thus made very small because of the vernier action of the control mechanism. This feature of the improved control mechanism provides for great flexibility in its design as well as in the design of the apparatus to be controlled. Also it makes the control mechanism very desirable for application to radio tuning units, with which it is illustrated in the drawings. It is to be understood, however, that its use is not to be so limited and that it may be applied to any controllable apparatus. By changing the relative rotation of parts thereof the control mechanism or unit is also capable of accomplishing a predetermined angular rotation of a rotary structure before locking the structure in a predetermined stop position.

As illustrated, each control unit consists of axially spaced rotary gear members supported for relative reversible rotation on their axes, and lost-motion means including an adjustable member intermediate the gear members and operatively connected with rotary gear means mounted on each gear member. On reversed rotation of the gear members the rotary gear means are successively locked with opposite portions of the adjustable member to in turn lock the gear members against relative rotation to define the predetermined position of the control apparatus, with the initial direction of rotation of the axis to such control position being determined by the direction of rotation of the rotary gear member initially overtaking the adjustable member. The gear ratio between the rotary means and the ad-

justable member may be any desired value so that the extent of lost motion in a control unit may be set at any predetermined value by merely changing the gear tooth size on the adjustable member and rotary means. The rotary means carried on a corresponding gear member are radially spaced from a corresponding adjustable member so that the space occupied by each control unit in a direction axially of the control shaft is very small. A relatively large number of the control units can thus be stacked within a relatively short space to provide maximum control within a compact mechanism.

Referring to the drawings, the improved control mechanism of this invention is illustrated in Figs. 1, 2, and 5 as applied to a radio preselector or tuning unit including a frame means 25 comprising a channel or U-shaped member 26 having inwardly bent flange portions 27 at each end 28 and 29 thereof. The ends 28 and 29 are closed by end plate members 31 and 31a, respectively, extended transversely of the frame member 26 and positioned inwardly of the corresponding flange portions 27 at the ends 28 and 29. The plate members 31 and 31a are rigidly secured to their corresponding flange portions 27 by welding or suitable like means, so that the assembly of the members 31 and 31a with the frame member 26 is of a substantially integral construction. A unidirectional driving motor 32 is mounted on the outside of the end plate 31a by supporting studs 33 extended through the laminated motor field structure 34. The motor shaft 36 is rotatably supported in strap or bearing members 37 secured to the field structure 34 by screws or the like 38. A pinion 39 (Figs. 1 and 21) is secured to the motor shaft 36 and is held in frictional engagement with the motor armature 40 by a spring washer 40a and collar 40b. Pinion 39 is in meshing engagement with a gear 41 mounted on a rotary driving shaft 42 which is rotatably supported in the end plates 31 and 31a. The gear 41 is in driving connection with the shaft 42 through flexible connecting means designated generally as 43 and including a driving spring 44. A centrifugal switch mechanism designated generally as 45 may be mounted on the outer end 36a of the motor shaft 36 for operating muting means 50 and remote control button interlock and release means 55 (Fig. 22) which will be herein-after fully described.

The driving shaft 42 (Figs. 1 and 5) is formed with an axially extending spline or groove 46 for receiving in mating engagement corresponding key portions 47 on a driving gear 48. A crank arm 49 is rotatably supported on the shaft 42 and positioned adjacent a gear 48 with each paired gear 48 and crank arm 49 being spaced axially of the driving shaft 42 by spacer members or collars 51. Thus the shaft 42 is rotatable relative to the arms 49. A corresponding gear and crank arm 49 are operatively associated with a corresponding control unit, which is designated generally as 52 (Fig. 2).

Each gear 48 is in continuous meshing engagement with a power-transmitting gear 53 (Fig. 5) which is rotatably supported at the end 54 of the crank arm 49, the gear 53 in turn being adapted for meshing engagement with a pinion 56 rotatably supported on a shaft 57. There is a gear 56 corresponding to each control unit 52 (Figs. 2 and 6), the gears 56 being spaced axially of the shaft 57 by spacer portions 58 integral therewith. A gear 53 is moved into meshing engagement with a corresponding gear 56, to operatively

connect a control unit selected for operation with the driving shaft 42, by pivotal movement of the crank arm 49 by means including an actuating magnet 59. From a consideration of Figs. 1 and 5, it is seen that the magnets 59 are extended transversely of the driving shaft 42 and positioned so as to attract thereto the end 61 of a corresponding crank arm 49. On attraction of the crank arm 61 in closing position with a corresponding magnet, as will be later described, the arm end 54 is pivotally moved an amount sufficient to provide for the complete meshing engagement of the gear 53 with a corresponding pinion 56. When the magnet 59 is deenergized the crank arm 49 is pivotally moved to a rest position against a stop member 64 by a coil spring 62 connected at one end to a tie rod 63 and its opposite end to the crank arm end 61. The driving spring 44 of the flexible connecting means 43 provides a small reverse rotation to the motor shaft 36 after the magnet 59 is deenergized to assure a positive disengagement of the gears 53-56.

Each pinion 56 (Figs. 2, 3, and 5) is in continuous meshing engagement with a rotary gear member 66 and a pinion 67. There is a pinion 67 corresponding to each control unit 52, the pinions 67 being rotatably supported on a shaft 68 in spaced axial alignment by spacer or collar members 69. Each control unit 52 includes a pair of similar gear members 66 and 66a, with a gear 66a being in continuous meshing engagement with a corresponding pinion 67. Since each control unit 52 is of a similar construction, only one thereof will be referred to in the following description.

The control units 52 are aligned axially of a rotary control shaft 71 (Figs. 2 and 5) having a gear 72 mounted at one end thereof, in continuous meshing engagement with a split spring tensioned gear 73 mounted on a shaft 74 for tuning means 76 illustrated as of gang condenser type. It is to be understood, however, that the improved control units 52 of this invention are also applicable for use with other type tuning means. The control shaft 71 and the condenser shaft 74 are suitably mounted in the end plates 31 and 31a preferably on ball bearings or other bearings having no lost motion. It is evident, therefore, that the condenser tuning means 76 is in driven connection with the control shaft 71 for rotation in either direction by means including spring tensioned bearings and gears, so that rotation of the control shaft 71 to a predetermined control position in turn accurately rotates the condenser 76 to a corresponding predetermined tuning position. From the above description and consideration of Figs. 1, 2, 5, and 6, it is evident that all of the axes means 42, 57, 58, 71, and 74 supporting the control mechanism are extended in parallel alignment longitudinally of the frame means 25 and operatively carried in the end plates 31 and 31a, with the elements carried on corresponding ones of the above-defined axes means being confined entirely within the frame means 25. The relative parallel alignment of the shafts 57, 68, and 71 is assured over all axial portions thereof at all times of operation by a retaining or spacing plate 75 (Fig. 5a) common to such three shafts and supported thereon intermediate their ends. The tuning unit is thus assembled as a very rigid and compact structure, with the frame means therefor being capable of absorbing high stresses without permanent distortion as occurs with the conventional staked or riveted frames now widely used.

As previously mentioned, each control unit 52 includes a pair of rotary gears 66 and 66a which are spaced axially of the control shaft 71 and operatively assembled with a corresponding adjustable gear member 77 (Figs. 6 to 8). The adjustable member 77 is freely rotatable and slideable on the control shaft 71 which, as shown in Fig. 7, is formed with a pair of oppositely positioned flat sides 78. The hub 79 for the adjustable member 77 is provided with end portions 81 and 81a of a reduced diameter for rotatably supporting at each end a corresponding one of the gear members 66 and 66a. The periphery of the hub 79 intermediate the end portions 81 and 81a is formed with gear teeth 80 with a tooth indicated as 80' being extended axially in both directions beyond the remaining teeth 80.

Each rotary gear member 66 and 66a has rotatably supported thereon a corresponding rotary gear or idler means 86 and 86a positioned inwardly of the gear members. As is clearly shown in Fig. 7, for the gear 66 the rotary means 86 is radially spaced from the adjustable member 77, with a rotary gear portion 87 thereof in continuous meshing engagement with the teeth 80 on the adjustable member for maintaining a predetermined operating relationship in a lost-motion means to be later explained. It is to be understood, of course, that the rotary gear means 86a is similarly operatively connected with the adjustable member 77. Since this operative connection with the adjustable member 77 is the same for each of the rotary means 86 and 86a, only the rotary means 86 will be referred to in the detailed description of these parts.

Referring to Figs. 7 and 8, the rotary gear portion 87 is seen to be rotatably supported on a rivet or axis means 88 extended through and secured to the gear 66. The rotary gear portion 87 is operatively connected with a locking portion 89 comprising a disc rotatable with the gear portion 87 and having a stop 91 extending radially between a pair of adjacent teeth on the gear portion 87. The locking portion 89 is positioned between the gear portion 87 and the rotary gear 66 so as to be radially spaced out of an engaging position with the teeth 80 on the adjustable member 77 (Fig. 8). However, since the long tooth 80' extends substantially between the gears 66 and 66a, each end thereof is in a radially spaced relation with a corresponding locking portion 89 and 89a. Relative rotation or lost motion between the rotary gear portion 87 and the adjustable member 77 thus takes place only so long as the stop 91 does not engage the stop or long tooth 80' on the adjustable member. When the stop 91 engages the stop 80' the gear 66 is locked in a fixed position relative to the adjustable member 77 so that the two may rotate together.

The lost motion occurring in the control unit 52 prior to a locking of the gears 66 and 66a with the adjustable member 77 may be established at any desired amount by merely changing the gear ratio between the idler gear 86 and the adjustable member 77. As illustrated in Fig. 7, the idler gear 86 is shown with 13 teeth, while the adjustable member 77 is shown with 12 teeth. With the stop portion 91 in an engaged position with one side the stop portion 80' on the adjustable member 77, the adjustable member 77 can be rotated twelve and a fraction complete revolutions in a direction out of such locking position before the stop 91 will again engage the stop 80' on the opposite side thereof.

It is seen, therefore, that the improved control mechanism of this invention is comprised of a determined number of rotatable operating elements, relatively assembled so as to occupy a space axially of the control shaft 71 substantially equal only to the axial length of an adjustable member 77. In one commercial embodiment, the overall length of the adjustable member is $\frac{1}{4}$ " and the diameter of gears 66 and 66a is $1\frac{1}{8}$ ". The control unit is thus compact in every direction, with its dimensions remaining unchanged over wide variations in the gear ratio between the idler gears 86 and adjustable member 77.

In the stacking of the control units 52 axially of the control shaft 71, each control unit 52 is separated from a next adjacent control unit by a washer or separating collar 82 having flat sides 83 for mating engagement with the flat sides 78 on the rotary control shaft 71 so as to be held against rotation relative to the shaft (Fig. 6). As noted, each of the reduced hub portions 81 and 81a are of an axial length greater than the thickness of a corresponding rotary gear 66 and 66a. Thus with the control units 52 axially stacked on the rotary control shaft 71, and in a spaced relation by virtue of the spacing washers 82, on their being clamped together as by clamping means designated generally as 84 (Figs. 2 and 6), the adjustable members 77 are frictionally locked between adjacent ones of the spacing washers 82 so as to be rotatable with the washers 82 and the shaft 71 as an integral unit. However, since the axial length of a reduced hub portion at each end of the adjustable member 77 is greater than the thickness of a corresponding rotary gear 66 and 66a, such gears are freely rotatable on the adjustable member for rotation relative thereto and to each other.

In the operation of a control unit 52 let it be assumed that the adjustable member 77 is in an adjusted position corresponding to a predetermined control position of the shaft 71 and, in turn, to a corresponding predetermined tuning position of the tuning means 76. This operation is best understood from Fig. 3 in conjunction with Fig. 7. As previously mentioned, the motor 32 is of unidirectional type and for the purposes of explanation let it be assumed that its rotation is in the counter-clockwise direction indicated by the arrow in Fig. 3. This direction of rotation in turn rotates the pinion 39 on the motor shaft 36 in a counter-clockwise direction and the gear 41 in a clockwise direction. With the gear 41 thus rotated, the driving shaft 42 and hence each driving gear 48 are also rotated in clockwise directions. Because of the continuous meshed engagement of a gear 48 with a power-transmitting gear 53, the latter is rotated in a counter-clockwise direction.

On pivotal movement of the crank arm by the magnet 59, as will be later fully explained, the gear 53 is moved from its full line position to the dotted line position shown in Fig. 3 in engagement with the pinion 56. This engagement rotates the pinion 56 in a clockwise direction to in turn drive the pinion 67 and gear 66, which are in continuous engagement with the pinion 56, in counter-clockwise directions. Since the pinion 67 is in continuous meshing engagement with the gear 66a, this gear is rotated in a clockwise direction or oppositely to the direction of rotation of the gear 66 in a corresponding control unit 52. By virtue of this reversed rotation of the gear members 66 and 66a their corresponding idler gears 86 and 86a, respectively, are reversely ro-

tated in opposite directions about the adjustable member 77 as indicated by arrows in Fig. 3. It is apparent that with the shaft 71, and hence the adjustable member 77 in a stationary position, that rotation of the idler gears is accomplished by their being rotated about the adjustable member by the gears 66 and 66a.

Because of the rotating lost-motion action of the idler members 86 and 86a relative to the adjustable member 77 the control shaft 71, and hence the tuning means 76, remain stationary until one of the gears 66 and 66a is locked with the adjustable member 77. Thus let it be assumed that the gear member 66 is initially locked with the adjustable member 77 in the manner above fully explained in connection with Fig. 8. When this locking occurs, lost motion between the idler gear 86 and member 77 is discontinued and the adjustable member and hence the control shaft 71 are rotated in a counter-clockwise direction corresponding to the direction of rotation of the gear member 66 as indicated in Fig. 3. Because of the reversed rotation of the gears 66 and 66a this rotation of the adjustable member 77 by the gear 66 accelerates the relative movement between the idler 86a and the adjustable member 77 to in turn accelerate the occurrence of the locking action between the adjustable member 77 and the gear 66a. Since the idler gears 86 and 86a are rotated in opposite directions relative to each other, and reversely about the adjustable member 77, the corresponding stop portions 91 and 91a thereof engage opposite ends and sides of the stop portion or long tooth 80' on the adjustable member. Since the driving force of the gears 66 and 66a acts on the tooth 80' in opposite directions, and since these opposed forces are equal, the coupled engagement of both gears with the member 77 locks such gears against further relative rotation to define the predetermined control position of the shaft 71. It is obvious, of course, that if the gear 66a is initially locked with the adjustable member 77 that rotation of the control shaft 71 will be in a direction corresponding to the direction of rotation of the gear 66a, or in a clockwise direction as indicated in Fig. 3, which rotation will continue until the gear 66 is also locked with the adjustable member 77. Because of the continuous meshing engagement of the adjustable member 77 with each of the idler gears 86 and 86a, a predetermined operating relationship is continuously retained between these three elements. Although the rotation of the motor 32 is unidirectional, the opposite rotation of the gears 66 and 66a provides for a rotation of the control shaft, and hence of the condenser 76, in either direction of rotation to a predetermined tuning position.

It is obvious, of course, that with a control unit in a locked condition resulting from one direction of rotation of the shaft 71, that rotation of the shaft may take place in an opposite direction to a degree corresponding to the lost motion in the control unit, until locking of the control unit is again accomplished. This establishing of a known lost motion may be used where it is desired to rotate the apparatus to be controlled through a predetermined angular distance prior to locking it in a stop position. A plurality of control units may thus be stacked on a single shaft without mutual interference, while permitting manual rotation of the shaft without requiring any disengagement of the control units.

A modified form of lost-motion means for a

control unit 52 is shown in Figs. 9 and 10. The adjustable element 77' is formed with reduced end portions 93 and 93a capable of receiving thereon gear elements 94 and 94a, respectively, for rotary gears 66 and 66a, respectively. The gear elements 94 and 94a are fixed on the member 77' as by a press fit or the like so as to be rotatable therewith as a unit. The axial extent of each reduced hub portion 93 and 93a is such that on clamping of the member 77' between the washers 82 the gears 66 and 66a are freely rotatable. The portion of the adjustable member 77' between the ends 93 and 93a thereof is formed with a single radially projecting tooth or stop portion 96 which extends axially of the member 77' between the gear elements 94 and 94a and in mating alignment with corresponding axially aligned teeth on the gear elements 94 and 94a. The elements 94 and 94a are in continuous meshing engagement with corresponding idler gears 92 and 92a. Since the lost motion or coupling means for each gear 66 and 66a is the same, only the means for gear 66 will be referred to in the detailed description of these parts.

The idler gear 92 is rotatably supported on a pin 95 mounted in the gear member 66, the gear 92 being positioned adjacent the gear 66 and radially spaced from the gear element 94 for continuous meshing engagement therewith. An annular portion 97 concentric with and rotatable with the idler gear 92 is positioned about the pin 95 in radial alignment with the stop or tooth portion 96 on the adjustable member 77. The annular ring 97 is integrally formed with a radially extending stop portion 98 for locking with the tooth 96 in a manner which is in all respects similar to the locking action previously fully described in connection with the stop 91 and the adjustable member 77 in Fig. 8. Since the operation of a control unit with the lost-motion means of Figs. 9 and 10 is similar in all respects to the operation as described in connection with the lost-motion means of Figs. 6-8, inclusive, a further description thereof is believed to be unnecessary. For rapid high speed tuning it is desirable to have the units somewhat resilient, and specifically the gears 66 and 66a capable of springing, so as to absorb the shock to the unit resulting from the impact which occurs when all stops in a unit are locked together at the pre-determined control position. The resiliency inherent in the units as described can be increased by using a thin spring-tempered metal for the gears 66 and 66a, and by removing portions thereof, indicated at 99 in Fig. 10, at the point of bending.

As previously mentioned, the adjustable members 77 for the control units 52 are held in their adjusted positions by clamping means 84. The clamping means 84 (Figs. 2 and 6) are mounted on the control shaft 71 together with means for limiting the rotation of the control shaft and include a pair of axially spaced gear members 101 and 101a rotatably supported on the shaft 71 but retained against rotation relative to the frame 25 by the locked engagement of the teeth thereon with stop clips 102 removably attached to the frame member 26 by screws 103. The member 104 intermediate the gears 101 and 101a is provided with flat key portions 105 for mating engagement with the flat shaft sides 78 so as to be slidably but non-rotatably supported on the shaft 71. Rotary means 86 and 86a identical in all respects to the like means used in the control units 52 are rotatably

carried on corresponding gear members 101 and 101a in continuous meshing engagement with the member 104. A locking nut 106 axially threadable on the shaft 71 is provided with a gear portion 107 for meshing engagement with a driving gear 108 fixed on the shaft 57 for the pinions 56. It is seen, therefore, that the pinion 108 is rotated with the shaft 57, as by the control knob 109, independently of any rotation of the pinions

10 56.

In the operation of the clamping means 84 assume all of the control units 52 in a clamped position. To release the adjustable members 77 for adjustment to new positions the shaft 57 is rotated in a direction to accomplish such release and, in turn, rotates the control shaft 71 and hence the member 104 through gears 108 and 107. Since the gear members 101 and 101a are retained against rotation, rotation of the member 104 continues until it is locked with one of the idler means such as 86 to limit any further rotation of the shaft 71. However, on continued rotation of the shaft 57, the clamping nut 106 is axially threaded away from the control units 25 52, or to the right as viewed in Figs. 2 and 6, until it engages the stop nut 110, so as to release the adjustable members 77. Some pressure is continued on the adjustable members 77 and nut 106 by a tension washer 111 to retain them against free rotation, the washer being supported on the shaft 71 between washers 111a and 111b, with the three-washer assembly in turn being intermediate the gear member 101a and the clamping nut 106. Since the locked position of the member 104 with each of the rotary means 86 defines the rotation of the shaft 71 in reversed directions, it is contemplated that this rotation be such as to permit rotation of the condenser 76 throughout a complete tuning range. Thus, 30 with the control units 52 in a released position, the manipulation of knob 109 rotates the condenser to any desired tuning position. With the knob 109 held manually to retain such tuning position, the control unit corresponding to the selected tuning position is actuated by pressing a button 117 to energize a corresponding magnet 59 and the driving motor 32, as will be herein-after described in connection with Fig. 14. This rotates the rotary elements of the control unit 45 to a locked position defining the adjusted position of the adjustable member 77 corresponding to the selected tuning position. Each of the control units is tuned in a like manner, with the adjusted position of each adjustable member 77 being retained by virtue of the frictional pressure retained between the control units 52 by the spring washer 111.

When all of the control units 52 have been 60 thus set, the shaft 57 is rotated in a direction for clamping the control units. This rotation of the shaft 57, in turn, rotates the control shaft 71 until locking is accomplished between the member 104 and the other one of the idler means 86 65 to stop the rotation of the shaft 71. The continued rotation of the shaft 57, however, axially tightens the clamping nut 106 against the control units 52 to positively retain the adjustable members in their adjusted positions, a suitable 70 stop portion (not shown) being provided at the shaft end opposite the nut 106 for retaining the units 52. The tuning unit is thus prepared for selective tuning.

In Figs. 11-13, inclusive, there is shown a radio 75 tuning unit which is substantially similar in all

respects to the tuning unit of Fig. 1 except for a modified form of driving means and clip arrangement for the stack clamping means for the control units 52. Thus, as shown in Fig. 12, the crank arms 49' are pivotally supported on the shaft 57 for the pinions 56, it being understood, of course, that a crank arm 49 and pinion 56 are individual to each control unit 52. The power-transmitting gear 53' on the crank arm end 54' is in continuous meshing engagement with the corresponding pinion 56. When the control unit 52 is in an idle position the gear 53' is out of meshing engagement with the driving gear 48', which position is indicated in Fig. 12. As shown in Fig. 11, the driving gear 48' is a pinion of elongated construction common to all of the control units 52. On energization of an operating magnet 59 for a control unit 52, therefore, the armature end 61' of the crank arm 49' is moved in a clockwise direction, as viewed in Fig. 12, to in turn pivotally move the crank arm end 54', whereby the power-transmitting gear 53' is engaged with the driving pinion 48'. When this engagement occurs, the control unit 52 is operated as was fully described above. On opening of the circuit for the magnet 59, as will be later explained, the gear 53' is moved out of meshing engagement with the driving gear 48' by the action of the spring 62'.

The clamping means 84' is similar in all respects to the clamping means 84 in Figs. 2 and 6 except that stop clip members 112 are used in place of the stop clip members 102. The construction provides for a standardizing of the parts used in the control units, rotation limiting stop means and clamping means whereby to decrease the manufacturing costs for the overall unit. The gears 101 and 101a of the rotation limiting means are identical in all respects with the like gears 66 and 66a of the control units 52, and although rotatably supported on the control shaft 71 are retained against rotation by the stop clips 112 secured to a portion 26a of the frame member 26 and adapted to be inserted between adjacent teeth on the gears 101 and 101a. Thus the gears 101 and 101a may be easily and simply fixed at any desired position to accomplish a predetermined rotation of the shaft 71 between the clamping and releasing positions of the clamping nut 106. Since the operation of the clamping means 84' is the same as that previously explained for the clamping means 84 in Fig. 6, a further description thereof is believed to be unnecessary. It is to be understood, of course, that a single gear member 101 or 101a could be used with a corresponding idler or lost-motion means for satisfactory operation with a stack clamping means.

The tuning structures disclosed in Figs. 1 and 11 may be utilized in either A. C. or D. C. circuits. By way of explanation, an A. C. circuit for these structures is illustrated in Fig. 14. The magnets 59 are connected in parallel between conductors 113 and 114 which are connected with an A. C. supply such as the secondary winding 100 of a power transformer 115 connected to a suitable source of supply 116 such as a 110 volt A. C. line. The motor 32 for operating the control units 52 is connected in series with each of the magnets 59 so as to be energized concurrently on energization of each magnet. It is evident, therefore, that on closing of a push button 117 the magnet 59 corresponding to the selected push button and the motor 32 are simultaneously energized. Thus, referring to Fig. 1, the rotary gears 48 are rotated simultaneously with the actuation of the

power-transmitting means 49-53 into meshing engagement with a pinion 56, while the corresponding parts in Figs. 11 and 12 are the elongated pinion 48' and the power-transmitting means 49'-53', which is moved into meshing engagement with the pinion 48'.

The radio "off" switch or button 118 is operatively associated with a control unit 52 and a magnet 59 in all respects similar to the same parts 10 operatively associated with each tuning button 117. The magnet 59 for the "off" button 118 is connected in parallel with the magnets 59 for the tuning buttons 117 from the common conductor 113, through the button 118, magnet 59, and conductor 119, the normally closed contacts 121 and 122 of a gang switch 123, and conductors 124 and 126 to the common conductor 114. The gang switch 123 also includes a contact 127 which is normally closed with the contact 122 to operate 15 the heater circuit designated generally as 128. Also included in the gang switch 123 are normally closed contacts 129, 131, and 132 for a rectifying circuit 133. As best shown in Figs. 12 and 13, the contact arms of the gang switch 123 are suitably mounted at one of their corresponding ends by means designated generally as 136 to the bottom or connecting portion 137 of the U-shaped frame member 26, the arms of the contacts 129, 131 and a spring arm 139 being arranged to operate in unison through a common insulated member 141. On movement of the member 141 toward the left as viewed in Fig. 14, or downwardly as viewed in Fig. 12, contacts 121, 122, and 127 are all opened to in turn open the heater circuit 128 20 and the "off" control circuit. In like manner the contacts 129, 131, and 132 are all opened at the same time to open the rectifying circuit 133.

In the operation of the control circuit of Fig. 14, let it be assumed that the tuning unit is in 40 operation at some selected tuning position, which condition is illustrated in Fig. 14, and that it is desired to shut the radio off. On actuation of the "off" button 118, the control unit 52 corresponding thereto is operated to move the condenser 76 to a predetermined control position at one of the extreme limits of its rotation. As shown in Figs. 1 and 12, the condenser shaft 74 has an actuating arm 134 mounted thereon for actuating the gang switch 123. On rotation of 45 the condenser 76 to an extreme clockwise limit, as viewed in Fig. 14, the arm 134 engages a cam follower portion 142 carried by the spring arm 139 to move the member 141 to operate the switch 123 as above described. When the switch has 50 been opened, the "off" control circuit is opened so that further actuation of the button 118 is ineffective to energize the magnet 59 corresponding thereto and the radio continues to be shut off until a station tuning button 117 is actuated.

55 Since the circuit for the magnets 59 and motor 32 is capable of being operated, even when the radio is shut off, a subsequent operation of any one of the tuning buttons 117 provides for a rotation of the condenser 76 out of its extreme position defined by the "off" button 118. Immediately on its rotation from such extreme position the gang switch 123 is permitted to operate to close the heating and rectifying circuits of the radio. It is evident, therefore, that any one of 60 the tuning buttons 117 automatically turns on the radio set while providing for its operation at a predetermined tuning position corresponding to the tuning button 117.

65 In Figs. 15-20, inclusive, there is shown a modification of the invention which is similar in many

respects to the embodiment in Fig. 1. Similar numerals of reference, therefore, will be used to designate corresponding parts.

The driving motor 32 is in driving engagement with the pinion assembly 56-67, through the pinion 39 on the motor shaft 36 and the gear 41, the gears 48a on the rotary drive shaft 42a being connected with corresponding pinions 56 and 57 for a control unit 52a. The power-transmitting gear 53 is rotatably supported on the crank arm 49a, which in turn is pivoted on the driving shaft 42a. The shaft 42a (Figs. 17 and 18) is formed with opposed flat portions 152 for keyed engagement with the gears 48a, mounted on the shaft 42a and internally formed with mating flat portions, there being a gear 48a for each control unit 52a. The crank arms 49a are rotatably supported on the shaft 42a and arranged between adjacent ones of the gears 48a. Each gear 48a is in continuous meshing engagement with the power-transmitting gear 53 which is freely rotatable on the armature end 61a of a crank arm 49a.

The armature 61a is attractable by a magnet 59, the magnets being vertically arranged in the unit as shown in Figs. 17 and 18. The action of magnet 59 on its corresponding armature 61a is opposed by the action of a spring 151 which is connected at one end to a projection 153 on the crank arm 49a, and at its opposite end to a tie rod or rail 154 carried in the tuner frame means. The armature 61a is held in an open position against a non-magnetic rest rail 156 by the spring 151. A brass stop or magnetic separator S is secured to the armature 61a in a position such that it engages the core of the magnet 59 when the armature is attracted thereto, so as to eliminate any possibility of the armature freezing to the magnet.

The pinions 56 and 57 are engageable with the gears 66 and 66a, respectively, of a control unit 52a. Besides the gears 66 and 66a each unit 52a includes an adjustable collar member 71a, with adjacent units 52a being spaced from each other by spacing washers 82a. The flat portions 78 formed on the shaft 71 are adapted for keyed engagement with corresponding flat portions formed internally of the spacers 82a. The adjustable member 71a is formed with a reduced section 157 and 157a at opposite ends thereof adapted to have a corresponding gear 66 and 66a freely rotatable thereon. In the assembly of each control unit 52a the adjustable collar member 71a with corresponding gears 66 and 66a thereon are alternately stacked with the spacing washers 82a on the control shaft 71. Since the mounting portion on each member 71a for the gears 66 and 66a is of an axial length greater than the thickness of such gears, the pressing together of the control units during their assembly on the control shaft 71 does not bind the gears 66 and 66a relative to the shaft 71 but serves merely to frictionally lock the adjustable members 71a between each adjacent pair of spacer members 82a. The frictional engagement of the members 71a in particular adjusted positions corresponding to predetermined control positions of the shaft 71 is obtained by the manipulation of suitable stack clamping mechanism designated generally as 158.

The adjustable collar member 71a for each control unit 52a is formed with a radially projecting but axially extending abutment 80a of rounded gear tooth contour. This abutment is formed and arranged for engagement with pinions 159 and 159a which are rotatably supported on pins 161 and 161a mounted in the face portion of gears

66 and 66a, respectively. In the assembly of each gear 159 and 159a a spring washer 162, as shown for the gear 159 in Fig. 19, is positioned about the pin 161 between the gear 159 and the pin head 163 to effect a slight drag or frictional pressure on the gear. This pressure is just enough to prevent the gear 159 from moving out of a predetermined meshing position with the abutment 80a during rotation of the gear 66. The toothed contour of each of the gears 159 and 159a is formed with a blank portion 164 (Fig. 18) which is substantially equal to the width of two gear teeth. With the adjustable collar member 71a fixed relative to the rotary control shaft 71, and the shaft 71 in a stationary position, it is seen that each complete rotation of gear 66, as shown in Figs. 17 and 18, rotates the gear 159 a distance equal to one tooth because of its engagement with the projection 80a on the member 71a. The progressive rotation of the gear 159 about the pin 161 continues until the portion 164 engages the tooth or abutment 80a, this coupled engagement serving to lock the member 71a and the gear 66 in fixed positions relative to the shaft 71 so that any further rotation of the gear 66 also rotates the shaft 71.

With the pinions 56 and 67 in continuous engagement with each other and arranged to rotate the gears 66 and 66a in opposite directions, the blank portions 164 on the idler gears 159 and 159a will engage opposite sides or portions of the tooth 80a. A locked engagement, of each gear 159 and 159a with the tooth 80a locks the gears 66 and 66a relative to the control shaft 71, this locked engagement defining a predetermined control position of the shaft 71. The gear 66 or 66a first connected in a coupled engagement with the adjustable member 71a by the locking action of its associated idler gear with the tooth 80a serves to rotate the shaft 71 in a given direction until a position is reached which brings about the coupled connection between the member 71a and the uncoupled gear, thus locking both gears 66 and 66a against any further rotation to define a predetermined control position. The adjustment of the members 71a to a desired setting of the control shaft 71 is obtained in a manner similar to that previously described for the members 71 in Fig. 1, the frictional locking of the members 71a being accomplished by the clamping mechanism 158.

Although the idler gears 159 and 159a are indicated as providing for a relative rotational movement of something over 12 revolutions between each of the gears 66 and 66a and member 71a, to correspond with a desired 12:1 driving ratio between the control shaft 71 and condenser 76, it is to be understood that the gears 66 and 66a and the pinions 159 and 159a can be altered in size and in the number of teeth thereon to provide for a wide variation in the free or lost motion of a control unit 52a. This variation in the lost motion of the control mechanism provides for a corresponding variation in the useful operating range of the control shaft 71, such range with the above 12:1 ratio being approximately 6.4 revolutions.

The structure of each control unit 52a thus provides for a high driving ratio between the control shaft 71 and the condenser 76 without increasing the bulk of the tuning device regardless of the driving ratio obtained. A very compact, precise and highly efficient tuning apparatus is thus provided which is readily applicable to a variety of tuning requirements.

A control circuit for the embodiment of Figs. 15-19, inclusive, is shown in Fig. 20. Although this control circuit is illustrated as being operated from a source of D. C. it is to be understood that the tuning structure of Fig. 15 may be operated equally well on A. C. In the latter case, a suitable A. C. motor is utilized, and with the non-magnetic spacer S being preferably made from a material such as neoprene or a tough fibrous vellum.

With reference to Fig. 20, on energization of a magnet 59 by a push button 166, the motor 32 is simultaneously energized through the double set of contacts 167 and 168 whereby the drive shaft 42a with the rotary gears 48a thereon is rotated substantially simultaneously with the actuation of the power-transmitting means 49a—53. That is, upon pushing a button 166, the corresponding magnet 59 is first energized by engagement of the button contact 165 with the battery contact 168. Continued pressure upon the button brings the contact 168 into engagement with the motor contact 167, the contacts 168 being in a common circuit.

The rotary gears 48a are engaged to rotate in a counter-clockwise direction, as viewed in Figs. 17 and 18, to rotate gear 53 in a clockwise direction. Rotation of the pinions 56 and 57 to oppositely rotate the control unit gears 66 and 66a actuates the coupling or lost-motion means 159 and 159a to couple the gears 66 and 66a with the adjustable member 71a. On rotation of the idler gears 159 and 159a into their respective locked positions with the tooth 80a, the gears 66 and 66a are locked with the control shaft 71, the control shaft 71 being rotated to a predetermined control position prior to such locking engagement in the manner previously explained. In practice, a push button 166 may be held closed until the shaft 71 has turned the condenser 76 to its predetermined tuning position.

With reference to Fig. 22, there is shown a modified form of the circuit of Fig. 20 which includes a remote control switch and latching means for holding the contacts 165, 167 and 168 closed after a button 166 has been operated, together with latch releasing means for opening the circuits after a tuning operation has been completed. The motor circuit includes the contacts 167 and 168 connected in parallel, with each pair of contacts being in series connection with the motor 32 and battery 195. The latching or interlocking means, designated generally as 55, is operatively associated with a centrifugal switch 45, previously mentioned, which is shown with the centrifugally actuated portion 170 thereof attached to the shaft 36 of the tuning motor 32. It is to be understood, of course, that any other shaft which rotates during the tuning operation and stops when tuning is completed may be operatively connected with the centrifugal switch. The switch portion 170 comprises a cylindrical housing 171 with a hub portion 172 for attachment with the motor shaft 36 by a set screw or other fastening means. Positioned within the housing 171 and extending radially inwardly thereof is an annular member 173 having openings 174 therein adapted to receive corresponding flyball members 176, two of which are shown. Each of the flyball members 176 has a reduced bell crank portion 177 which passes through a corresponding slot or opening in the annular portion 173. The flyball members 176 are thus pivotally supported in the annular portion 173. On rotation of the housing 171 the flyball members

176 are rotated therewith, centrifugal force moving the pawl member ends 178 radially outwardly toward the housing 171 to in turn move the inner bell crank portions 177 in an axial direction, into operative engagement with the end 182 of a slideable pin 179 slidably supported by bearing means 181 in coaxial alignment with the motor shaft 36. The opposite end 183 of the pin 179 operates the switch contact arm 186.

The switch unit 45 may comprise any convenient arrangement of contacts for carrying out any desired series of functions associated with the operation of the tuner. As shown in Figs. 21 and 22, it is comprised of three leaves or contact arms 184, 186, and 187. The contact 186 which is engageable with the pin 179 has sufficient spring tension therein so that when the motor shaft 36 is not rotating it is held in a normally closed position with contact 184. Contacts 184 and 186 are thus normally closed and contacts 186 and 187 normally open.

In the operation of the tuning circuit of Fig. 22, pushing in of a push button 166a successively closes the contacts 167, 168, and 165 corresponding to the selected push button, which is retained in an operated position by a latch bar 188 and a co-operating stop portion 189 on the push button in a well known manner. The flyball members 176 in the centrifugally actuated portion 170 of the centrifugal switch operate on the slideable pin 179 to move the contact 186 to an open position relative to the contact 184 and into a closed position with the contact 187, the closing of the contacts 186 and 187 providing for a muting of the speaker output. It is to be understood, however, that these contacts may be connected into other circuits of a radio receiver so as to perform some other function during a tuning operation.

When the tuner has completed its cycle of operations the motor 32 stalls, by virtue of the locking action of the control mechanism for the tuning means, to in turn reduce the centrifugal force acting on the ball members 176 and permitting the spring contact 186 to operate against the slideable pin 179 and into a closing position with the contact 184. On closing of the contacts 184 and 186, a circuit is closed from the ground connection 188 through contacts 186 and 184, conductor 189, solenoid 191, conductors 192 and 193, closed contacts 168 and 167, and conductor 194 to the battery 195. The energization of the solenoids 191 operates a core member 196 operatively connected with the latch bar 188 to pull the same out of an engaging position with the stop portion 189 of a push button 166a, whereby to release the operated button and open the contacts 165, 168, and 167. Since the solenoid 191 receives its energy from the same contacts 167 and 168 which energize the motor, the release of the push button 166a deenergizes the trip and motor circuits even though the contacts 184 and 186 remain closed after all tuning operations are completed. In other words, two sets of contacts 184—186 and 167—168 must be closed to energize the solenoid 191, which condition exists only momentarily during the latch tripping operation and when the motor 32 first stalls at the end of a tuning operation. Thus the push button is automatically retained in an operated position substantially immediately on initial actuation thereof, and is automatically released on completion of tuning operations concurrently with a stopping of the operating motor.

From a consideration of the above description and drawings, it is seen that the invention pro-

vides control mechanism adapted to accomplish a setting of reversible controllable apparatus in either direction of rotation to a predetermined control position. The invention provides also for a controlled rotation of controllable apparatus through a defined angular distance prior to its being stopped in a predetermined control position. The control mechanism is comprised of a predetermined number of rotatable elements which may be relatively constructed to provide for any desired extent of lost motion in the mechanism prior to a locking thereof to define a predetermined control position by merely changing the gear ratio between certain of such rotatable elements. A high degree of flexibility in accurately bringing the structure to be controlled to a predetermined control position is thus simply accomplished without in any manner changing the size of the control mechanism or the elements with which it is operatively associated. All of the parts are of a construction such that they may be machined by stamping them out from sheet metal or by performing a minimum number of simple machining operations on commercially available stock material. A precision mechanism is thus capable of being produced economically and on a high production basis.

Although the invention has been described particularly as applied to a radio tuning unit, it is not to be so limited, since it is apparent that it is readily adaptable to other types of controllable apparatus designed to operate at a plurality of control positions which may be anywhere within in a useful operating range for the controllable apparatus.

It is to be understood that the invention has been described with reference to specific embodiments thereof and that changes can be made therein which are within the full intended scope of this invention as defined by the appended claims.

What is claimed is:

1. Mechanism for accomplishing a positive locking in a rotary moving structure including in combination a pair of members with one of said members being rotatable relative to the other, rotary means rotatably supported on said one member for movement relative to said one member in response to relative movement between said pair of members, stop means on said other member, with said rotary means having a portion for maintaining said rotary means and other member in a predetermined operating relationship, and a stop portion on said rotary means operatively engageable with said stop means to lock said two members and rotary means in fixed relative positions.

2. Mechanism for accomplishing a positive locking in a rotatable structure including in combination a pair of coaxially mounted members, with one of said members being rotatable relative to the other, rotary means rotatably mounted upon said one member radially of said other member for rotation in response to relative rotation of said pair of members, stop means operatively connected to each of said other member and rotary means for locking said pair of members against further relative rotation after a predetermined angular movement thereof, and means for maintaining said rotary means and other member in a predetermined operating relationship.

3. Mechanism for rotating a control shaft in either direction of rotation to a predetermined control position including in combination a pair

of freely rotatable driving members, means rotating said driving members in opposite directions, an engaging member on said control shaft and common to said driving members, rotary means rotatably carried on each driving member for operative engagement with said engaging member, with said engaging member acting on said rotary means to rotate the same on rotation of said driving members, and a stop portion on each of said rotary means and engaging member for locking said driving members and engaging member in fixed relative positions to define said predetermined control position.

4. Control mechanism for defining a predetermined control position in controllable apparatus including in combination a rotary member operatively connected with said controllable apparatus, a pair of elements axially spaced on said rotary member and rotatably supported thereon for relative rotation, means for rotating said pair of elements in opposite directions, a third element supported in adjustably fixed position on said rotary member intermediate said pair of elements, rotary means rotatably mounted on each of said pair of elements radially spaced from said third element for operative engagement therewith, said third element on rotation of said pair of elements acting on said two rotary means to rotate each rotary means relative to a corresponding one of said pair of elements, means retaining each of said rotary means in a predetermined operating relationship with said third element, and a locking portion for each of said rotary means and third element and movable therewith for locking said third element and pair of elements in fixed positions to define said predetermined control position.

5. Mechanism for accomplishing a positive stop for a rotary means at a predetermined position, including in combination a plurality of rotary members, an engaging member on said rotary means, means for operatively connecting said engaging member and said plurality of rotary members including lost-motion means having a rotatably mounted member, and axis means rotatably supporting said rotatable member on one of said rotary members at a point spaced radially from the rotary means, with said rotatable member having a portion for engaging said engaging member to drive said engaging member and rotary means therewith to a stop position.

6. Mechanism for reversely rotating a control shaft to a predetermined control position including in combination a pair of axially spaced and freely rotatable rotary members, means driving said pair of rotary members in opposite directions, means for locking said pair of rotary members against relative rotation to define said predetermined control position including gear means mechanically coupled to said shaft, said gear means having a stop portion thereon, rotary means rotatably mounted on each of said rotary members having a gear portion in meshing engagement with said gear means, said gear means on relative rotation of said rotary members acting on said gear portions to rotate the same in opposite directions, and stop means operatively connected with each of said gear portions for rotation therewith, and engageable with said stop portion of said gear means to define said predetermined control position.

7. A control unit for moving reversible controllable apparatus in either direction to a predetermined control position including in com-

bination a rotary shaft operatively connected with said controllable apparatus, a pair of rotary members supported for free relative rotation, a toothed pinion mechanically coupled to said shaft intermediate said pair of rotary members and having one tooth projecting axially in both directions beyond the ends of the remaining teeth thereof, rotary means mounted on each of said rotary members, each of said rotary means having a gear portion radially spaced from said pinion for meshing engagement with all of the teeth thereof, and a stop portion rotatable with a gear portion to engage said projected tooth for locking said pinion in a fixed position with a corresponding rotary means, with the locking of both of said stop portions with said projected tooth stopping said rotary members against further relative rotation and defining said predetermined control position.

8. Mechanism for rotating controllable apparatus in either direction of rotation to a predetermined control position including in combination a rotary shaft operatively connected with said controllable apparatus, a pair of rotary member rotatably supported in an axially spaced relation for free relative rotation, means rotating said rotary members in opposite directions, adjustable means mechanically coupled to said shaft intermediate said pair of rotary members including a gear portion corresponding to each rotary member and a stop portion common to said pair of rotary members, rotary means mounted on each of said rotary members having gear means in meshing engagement with a corresponding gear portion on said adjustable means, and stop means for each of said rotary means operatively connected for rotation with a corresponding gear means and engageable with the stop portion on said adjustable means, with said predetermined control position being defined when both of said stop means are in locking engagement with said stop portion.

9. Mechanism for reversely rotating a control shaft to a predetermined control position including in combination a pair of axially spaced rotary members mounted for free relative rotation, means for driving said pair of rotary members in opposite directions, means for locking said pair of rotary members against relative rotation to define said predetermined control position including an engaging member mechanically coupled to said shaft intermediate said rotary members and having an axially extending tooth portion thereon, gear means rotatably carried on each of said rotary members for operative engagement with said tooth portion, said tooth portion on relative rotation of said rotary members acting on said gear means to rotate the same in opposite directions, and a stop portion included in each of said gear means for engaging said tooth portion to lock a corresponding rotary member with said engaging member, with the locking of both of said rotary members with said engaging member defining said control position.

10. Control mechanism for defining a predetermined control position in controllable apparatus including in combination a shaft, a pair of oppositely rotatable members on said shaft, engaging means on said shaft, and rotary means rotatably mounted on each of said pair of members and each rotary means including a stop portion rotatable therewith, with each rotatable member and corresponding rotary means being relatively rotatable and rotatable relative to said

engaging means until a locked position of the corresponding stop portion is attained, and said control mechanism being operable until both stop portions are in locked positions at a predetermined control position for said mechanism.

11. In a control system for a radio apparatus including a plurality of control units for selectively moving tuning means to predetermined tuning positions, said tuning means being movable between two extreme limits, electrical means for operating said control units, a circuit for said electrical means including switch means corresponding to each of said control units, means corresponding to each control unit for actuating a corresponding switch means, circuit means for said radio apparatus including switch control means electrically connected with said electrical means, and means movable with said tuning means for moving said switch control means, 10 when said tuning means approaches one of said extreme limits of movement, to render said electrical means and circuit means inoperative, one of said control units being adapted to provide for the movement of said tuning means to said 15 one extreme limit, with the later operation of any one of the actuating means corresponding to the remaining control units operating said electrical means to move said tuning means and said switch control moving means therewith to release said switch control means and permit operation of said circuit means at the tuning position corresponding to the later actuated control unit.

12. A preselecting mechanism comprising a shaft having a rotational range of over 360°, a coupling member normally rigid on said shaft, a pair of rotary intermittent movements, each movement having a power input and output with a step-down ratio at the output, means on each movement for defining a range of free angular travel, means for supplying power to said movement inputs tending to operate them at equal speeds, means connecting said movements and coupling member for transmitting force directly 40 to said coupling member for shaft rotation when each movement has reached the end of its free travel range, said two movements tending to turn said shaft in opposite directions, and locking means for maintaining the relative positions of 45 the parts of each movement to each other and to the coupling member, each movement having a free travel range corresponding to the shaft range, said locking means preventing range displacement and said movements tending to take 50 up the free travel range and thereafter tending to turn said shaft until equal and opposite shaft turning forces define a preselected point.

13. A preselecting mechanism comprising a shaft having a rotational range of over 360°, a pair of drive members spaced axially of said shaft and each rotatable around said shaft, means for rotating said drive members at equal speeds in opposite directions, gears to be individually actuated by said drive members and each 60 mounted eccentrically to said shaft, means disposed between said drive members and including a part normally rigid on said shaft for rotating said gears in opposite directions in response to rotation of said drive members in opposite directions about said shaft, and means controlled by movement of each gear for establishing a locking connection between the associated drive member and said shaft when the gear is rotated to a predetermined position, whereby said drive members will be actuated until both of said gears 70

have reached their locking positions to determine a stationary preselection point for said shaft.

14. A preselecting mechanism comprising a shaft having a rotational range of over 360°, coupling means normally rigid on said shaft, a drive member rotatable around said shaft on each side of said coupling means, means for rotating said drive members at equal speeds in opposite directions, a gear train between each driving member and said coupling means, each of said gear trains including a first gear mounted eccentrically to said shaft and a second gear meshing with said first gear and means on one of said gears for establishing a locking connection between the associated drive member and said coupling means when predetermined teeth of the two gears are engaged, whereby said drive members will actuate said gear trains until both have reached locking positions to determine a stationary preselecting point for said shaft.

15. A preselecting mechanism comprising a shaft having a rotational range of over 360°, a pair of rotary intermittent movements each including means defining a range of free angular travel, each of said movements having a power input and a power output, means for supplying power to said movements tending to operate them at equal speeds, coupling means for transmitting force directly to said shaft for shaft rotation when each movement has reached the end of its free travel range, said two movements tending to turn said shaft in opposite directions, and means for maintaining the relative positions of the parts of each movement to each other and to the coupling means, said last-named means preventing range displacement and said movements tending to take up the free travel range and thereafter tending to turn said shaft until equal and opposite shaft turning forces are exerted on said shaft to define a preselected shaft setting.

16. A preselecting mechanism comprising a shaft rotatable over a range in excess of 360°, a pair of gears mounted to rotate on axes offset to but parallel with the shaft, each gear having an associated locking means rotatable therewith which can co-operate with a meshing member to determine a range of gear rotation, toothed means carried by said shaft for turning said gears throughout their respective travel ranges and for co-operating with said locking means to lock the gears at the ends of their travel ranges, and means for producing opposite relative movements of equal speeds between said gears and said toothed means until the preselection point is reached whereupon the equal and opposite shaft turning forces prevent further shaft movement.

17. Mechanism for reversely rotating a control shaft to a predetermined control position and for then arresting the rotation of said shaft, said mechanism including, in combination, a pair of axially spaced rotary members freely rotatable on said shaft, means for driving said members in opposite directions, and means for locking said pair of members against relative rotation to define said predetermined shaft control position including a pair of toothed members disposed between said members, axis means supporting said members for rotation about axes which are parallel to but radially displaced from the axis of rotation of said shaft, toothed means carried by said shaft and operative to rotate each of said toothed members a fraction of a revolution about its axis of rotation in response

to each revolution of the associated rotary member about said shaft, and stop means associated with each of said toothed members for rotation therewith, and engageable with tooth parts of said toothed means to define said predetermined shaft control position.

18. In control apparatus for rotating a rotary control shaft in either direction, a control unit operative to rotate said shaft in either direction to a predetermined setting and comprising, in combination, means including a lost-motion mechanism for rotating said shaft in one direction to said predetermined setting and for arresting the rotation of said shaft when it is rotated to said predetermined setting from the opposite direction, a rotatable element, means supporting said element for rotation about an axis parallel to but spaced radially from said shaft, means for rotating said element about said axis during operation of said first-named means, and stop means controlled by said element to provide a connection for rotating said shaft in said opposite direction to said predetermined setting and for arresting the rotation of said shaft when it is rotated to said predetermined setting from said one direction.

19. Rotary control mechanism for defining a locked position for controllable apparatus comprising, a pair of coaxially aligned relatively rotatable rotary members, a first lock portion on one of said members, a second lock portion on the other of said members, and means for effecting rotation of said second lock portion relative to said other member in response to relative rotation of said pair of members and for effecting operative engagement between said first and second lock portions in predetermined relative positions thereof to define said locked position of said apparatus.

20. Rotary control mechanism adapted to be rotated through an angular distance to a locked position with controllable apparatus, including in combination an engaging member connected with said controllable apparatus and two elements supported for rotary motion relative to each other and to said engaging member at all positions other than said locked position, axis means on one of said elements for supporting the other of said elements in a position for rotation by said engaging member, and stop means corresponding to said other element and to said engaging member and movable upon movement of said other element into a position for locking said two elements and member against further relative movement.

21. A preselecting mechanism comprising a shaft having a rotational range of over 360°, a coupling member normally rigid on said shaft, a driven toothed member on each side of said coupling member rotatable about an axis parallel and eccentric to said shaft, a driving toothed member for each of said driven members to form two pairs of co-operating toothed members, each driving toothed member forming an intermittent movement with the co-operating driven member, means for locking each of said driven members against idle rotation, means defining an angular range of rotation of said driven members, said ranges being substantially equal to the shaft range and operatively coincident, and means for turning said driving members at equal speeds and in a direction to result finally in opposing shaft-turning forces, said intermittent movements taking up their respective travel ranges

at equal speeds and then turning the shaft until equal and opposite shaft-turning forces determine a preselected position.

22. A preselecting mechanism comprising a shaft having a rotational range of over 360°, a pair of toothed members rotatable about axes eccentric to but parallel with said shaft, each toothed member having an associated stop means rotatable therewith which is co-operable with toothed means to determine a free travel range of rotation of the toothed member, toothed means carried by said shaft for rotating said toothed members about their axes until their respective free travel ranges are taken up and for then co-operating with said stop means to exert shaft-turning forces on said shaft, locking means restraining said toothed members against rotation except when being rotated by said toothed means, thereby to prevent inadvertent relative movement between said toothed members and said toothed 20

5

means and thus prevent displacement of the free travel ranges of said toothed members, and means for so moving said toothed members and toothed means relative to each other that the free travel ranges thereof are taken up and then equal and opposite shaft-turning forces are exerted on said shaft to define a preselected shaft setting.

HAROLD F. ELLIOTT.
